UNITED STATES PATENT OFFICE.

JOHN FORST, JR., OF BOSTON, MASSACHUSETTS.

PENHOLDER.

1,064,634.

Specification of Letters Patent. Patented June 10, 1913.

Application filed February 7, 1913. Serial No. 746,875.

To all whom it may concern:

Be it known that I, JOHN FORST, Jr., a citizen of the United States, residing at West Roxbury, Boston, in the county of 5 Suffolk and State of Massachusetts, have invented new and useful Improvements in Penholders, of which the following is a specification.

The invention relates to stationery, more 10 particularly to writing materials, and has for an object to provide a pen holder whereby the pen nib can be easily attached thereto or as readily removed therefrom.

The invention contemplates, among other 15 features, a pen holder whereby the handle of the holder together with suitable spring-like members normally secure the nib to the holder, the nib being received in a collar having a portion of the handle extending 20 therein so that when the handle is removed from the collar, the spring-like members will be released so that the nib will gravitate 25 from the collar, thus obviating the necessity of manually removing the nib from the collar and which, particularly when the nib is covered with ink, is a disagreeable task.

In the further disclosure of the invention reference is to be had to the accompanying drawings, constituting a part of this specification, in which similar characters of reference denote corresponding parts in all the 30 views, and in which:

Figure 1 is a vertical longitudinal sectional view of the pen holder, showing a nib secured therein; Fig. 2 is a similar view, showing the handle of the holder removed from the collar, with the nib removed from the collar; Fig. 3 is a vertical transverse sectional view taken on the line 3—3 in Fig. 40 1; and Fig. 4 is an end view.

Referring more particularly to the views, I disclose a pen holder 10 including a collar 11 and a handle 12 provided with a reduced end 13 adapted for insertion in the collar 11. 45 A plurality of spring-like clamping members 14 have their inner ends secured to the inner end of the collar and lying within the same, the said spring-like members being

semi-circular in cross section, with the front ends of the members normally tending to 50 engage, as shown in Fig. 2.

Now when it is desired to secure a nib 15 to the pen holder 10, the nib is inserted in the front end of the collar 11, after which the handle 12 is engaged with the collar 11, 55 thus causing the reduced end 13 to engage the spring-like clamping members 14 and press the forward ends thereof toward the wall of the collar, thus clamping the inner end of the nib between the wall of the 60 collar and one of the spring-like clamping members. When it is desired to remove the nib without touching the same, it is simply necessary to remove the handle 12 from the collar 11, thus permitting the spring-like 65 clamping members to return to normal position and out of clamping position, thus releasing the nib which will gravitate from the collar and become entirely disengaged 70 therefrom.

It will be readily apparent that the collar and handle can be constructed of rubber, wood or metal and that the article including the spring-like clamping members can be cheaply and durably manufactured at small 75 cost. It will be further apparent that when the spring-like clamping members are in clamping position the nib will be securely held in the collar by one of the members, and which force the nib against the wall of 80 the collar. It will be further apparent that only one of the spring-like clamping members is necessary, although two are preferably employed so that the nib can be inserted in the collar to be engaged by either 85 one of the clamping members or the other.

Having thus described my invention, I claim:

1. As a new article of manufacture, a pen holder comprising a collar, a plurality of 90 curved spring-like members having their inner ends secured to the inner end of the collar and their forward ends normally in engagement, and a handle adapted to be inserted in the inner end of the collar to engage 95 the spring-like clamping members and

move the same toward the wall of the collar to clamp a nib between one of the members and the wall of the collar.

2. In a pen holder, the combination with 5 a collar, of spring-like clamping members supported therein, with the forward ends thereof normally spaced from the wall of the collar, and a handle for removable insertion in the collar to engage the spring-like mem-

bers and move the same into position to 10 clamp a nib against the inner wall of the collar.

In testimony whereof I affix my signature in presence of two witnesses.

JOHN FORST, JR.
